KEEL-BLOCKS

Edmond Raymond Casas, Marseille, France, assignor to Ateliers Provencaux de Reparations Navales et Industrielles, Marseille, France, a corporation of France
Filed Apr. 4, 1962, Ser. No. 184,993
Claims priority, application France, Jan. 16, 1962, 884,973
8 Claims. (Cl. 61—66)

This invention has for its object a line of keel-blocks, or like supporting system for a ship in dry dock, or for similar applications.

Lines of keel-blocks resorted to hitherto are arranged so that there are inserted, between a base and planks or like elements supporting the ship's hull, wedge-shaped bearing members disposed symmetrically on either side of the longitudinal plane of symmetry of the line of keel-blocks, the clamping effect being obtained by means of built-in jacks. In such known systems the wedges are parts having an outwardly and downwardly inclined bottom surface and an outwardly and upwardly inclined top surface, as a result of which two wedges will have a common summit and bases directed towards opposite sides. This in turn requires that the supporting planks be cut accordingly, i.e. that their lower surfaces be inclined so that they can fit into the cup formed by the outer and top surfaces of the two wedges. The wedges and the planks are then tightened against the hull of the ship, using convenient devices built into the blocks, for example, jacks or the like.

It will be appreciated that such stocks have serious drawbacks in that they require the incorporation and operation of a large number of jacks. Indeed, it is necessary to have at least two jacks available per set of two wedges. In addition, the planks must be especially shaped and be made in one piece (at least in cross-section) so that on dismantling, and when the two wedges are moved away from each other, a plank may move downwards evenly. In order to loosen the wedges, a force operating from outside must be applied, i.e. a pull must be exerted, and this can be particularly inconvenient in that it becomes necessary to operate on the two lateral sides at once with equal force in order to prevent the whole structure from collapsing.

The line of blocks according to this invention enables these drawbacks to be overcome. It is noteworthy in particular in that it comprises, on the one hand, a series of substantially parallel rows of vertical barrels of identical height which form a base and which are disposed at right angles to the longitudinal axis of the line of blocks and rest on the ground or on a dry dock apron, the barrels of each row, which are bevelled at their tops, being interconnected by an inclined joining plate, and, on the other hand, a corresponding row of wedge means, each resting on said inclined joining plate through the medium of a bottom plate which has a matching degree of inclination and being provided at its summit with a top plate which is substantially horizontal when the wedge rests on the row of corresponding barrels, the top plate of each wedge in turn supporting, through the medium of a plate forming a sole, one of said supporting planks, in such manner that by applying temporary pulling or pushing forces it be possible to engage or disengage said wedge means in order to respectively clamp or dismantle the corresponding row in the line of blocks.

In accordance with a further feature of this invention, the aforementioned inclined plates affixed to the bevelled summits of the barrels forming the base of a given row, slope in the direction of the line of blocks, while those of the adjoining rows are inclined in the opposite direc-

2

tion (or vice versa), this disposition being repeated throughout the length of the line of blocks.

In accordance with another feature of the invention, removable means are provided to render said barrels, 5 wedges and the plates forming plank soles mutually rigid.

The description which follows with reference to the accompanying drawings, given by way of example only, will give a clear understanding of how the invention may be carried into practice and will disclose still further 10 features thereof.

In the drawings filed herewith:

FIGURE 1 is a side elevation view diagrammatically showing a line of blocks according to the invention;

FIGURE 1A is a larger-scale detail view of FIGURE 15 1, showing a wedge means and a supporting plank resting thereon the clamping stirrups being omitted;

FIGURE 1B is a detail view similar to FIGURE 1A showing a clamping stirrup in operative position;

FIGURE 2 is a front elevation view of an assembly 20 of barrels constituting the portion which forms the supporting base of the line shown in FIGURE 1;

FIGURE 3 is a section taken through a horizontal plane along the line 3—3 in FIGURE 2, showing the base of the assembly in FIGURE 2;

FIGURE 4 is a front elevation view of an element 25 forming a wedge;

FIGURE 4A is a larger-scale view of a detail in FIGURE 4;

FIGURE 5 is a plan view of a keying means of 30 assembling together two adjacent elements of the line of blocks;

FIGURE 6 is a sectional view taken through the line 6—6 of FIGURE 5;

FIGURE 7 is a perspective view of one of the stirrups 35 used to assemble the elements of the line of blocks in FIGURE 1; and

FIGURE 8 is a perspective view with partial cutaway of one of the stirrups used for dismantling the elements in a line of blocks.

40 Referring now to FIGURE 1, there is diagrammatically shown thereon a line of blocks according to the invention disposed between a ship in dry dock, the bottom of which is designated by the reference numeral 10, and a dry dock apron 11. The principal elements constituting the

45 line of blocks shown in side elevation in FIGURE 1 consist basically of alignments or rows of supporting barrels 12, wedge-shaped pieces 13 and planks 14 in contact with the bottom of the ship. The base assembly 12 is shown in front elevation in FIGURE 2 and, in cross-section along a horizontal plane, in FIGURE 3. In the example illustrated, the base 12 consists of four tubular members with vertical axes 15, 16, 17 and 18, adjacent generatrices of which are interconnected by vertical plates 19, 20 and 21 forming spacers. The tubes 15—18, as

50 well as the spacer plates 19—21, are preferably made of steel and assembled together by welding. The tubes 15 and 16 rest upon the base plate 22 to which they are welded, and the tubes 17 and 18 rest on a base plate 23 to which they are likewise welded. Angles 24 are welded

55 respectively to said vertical tubes and to the base plates on which said tubes rest, such a disposition contributing to reinforce the structure of an elemental stock. The tubes 15 through 18 are bevelled at their tops, as may be clearly seen from the side elevation view of FIGURE 6 and a flat inclined plate 24 is affixed, by welding for example, to the top of a transverse row of tubes.

60 The piece forming wedge means, which is generally referred to by the reference numeral 13, rests on the inclined plate 25. The said piece 13 is shown in front elevation in FIGURE 4 and in side elevation, on a larger scale, in FIGURE 1A. In the specific example shown

in FIGURES 4, 1A and 4A, the piece 13 acting as wedge means comprises four tubular members 30, 31, 32 and 33. These tubular members are bevelled at their bases at the same angle as the tubular members 15 through 18, and their tops are coplanar. The bases of the members 30-33 rest upon a plate 34, to which they are welded: said members 30-33 are spaced to be located substantially over those subjacent tubular members of the base 12 which have been designated by the reference numerals 15-18. It will be appreciated that it will be particularly advantageous to construct the members 30-33 from tubes of the same type as those used for members 15-18. The said members 30-33 support a horizontal plate 35 which is welded to their tops. To the lateral ends of the plate 34 and beneath it are welded flat irons 36 and 37 the spacing between which is substantially equal to the length of the upper plate 25 of the base member 12 and the thickness substantially equal to that of said plate 25, whereby the flat members 36 and 37 form guideways which facilitate location of the wedge 13 on the base 12. To the edge 38 of the upper plate 35 of wedge 13 is welded a plate 39 which forms an abutment for the sole of the plank-sole assembly which will be described hereinafter. (See FIGURES 1A and 4A.)

The plank 14 is mounted on a plate forming a sole 40, to which it is fixed by four tabs or lugs 41 which are drilled to co-operate with securing screws or the like (not shown), the said lugs 41 being themselves disposed on longitudinal flats affixed to the edge of the sole plate 40 and denoted by the reference numeral 42. The sole plate 40 is substantially longer than the plate 35 upon which it rests, and at its two projecting lateral ends are disposed, beneath the plate 40, flats 43 which contribute to guiding said plate 40 on the plate 35. The plank 14 proper is preferably made of some wood which is suitable for such a use, examples being azobe wood or poplar, while the sole plates 40 and the longitudinal flats 42, together with the lugs 41, are made of steel or weldable iron of the same type as the other parts of the blocks to which reference has been made precedingly.

The foregoing description has been given with reference to one of the supporting elements in the form of a row of barrels upon which rests a plank, with an intervening wedge. The line of blocks, as it is illustrated diagrammatically in side elevation in FIGURE 1, comprises a certain number of rows identical to that herein-after described but the overall disposition of which is preferably in conformance with that of FIGURE 1. In other words, for two adjacent rows of vertical barrels, the orientation of the wedges is different. Thus, designating the rows of supports from left to right on FIGURE 1 by the letters A, B, C, D, etc., the wedges of rows A and B converge towards the space comprised between these two rows, while the wedges of rows C and D converge towards the space comprised between rows C and D. It will be appreciated that, with such a disposition, the elements in the rows A and B may be tightened by means of a jack which is placed between the wedges 13 of rows A and B and which tends to move said wedges towards one another. This likewise applies for tightening the wedges 13 of rows C and D by moving said wedges 13 in these rows towards one another. It is evident, however, that the same tightening of rows B and C may be obtained by disposing in the space comprised between the same a jack which is applied against the wedges 13 therein and which tends to move said wedges away from one another. The loosening operation in the case of rows A and B, or C and D, may be obtained, for instance, by moving the wedges in these rows away from one another by the thrust of a jack disposed between said rows A and B or C and D. Of course it will be understood that the same result can be obtained by means of a tractive force exerted by a jack disposed between rows B

and C, adapted to pull the wedges 13 thereof towards one another.

Referring now to FIGURES 5 and 6, there is shown thereon, in plan and section view respectively, a means for providing a keyed joint between base plates 22 (or 23) of two adjoining rows of barrels. In addition, this joining means is of simple type. As may be seen from FIGURES 3, 5 and 6, there are welded to the corners of said plates 22, parts 45 shaped as half-rings and made, for instance, of a plate which is flexed and welded by its edges to the sole 22 (or 23) of the structure supporting the barrels 12. It will be sufficient with such an arrangement to appropriately dispose the plates 22 and 23 of two adjoining rows opposite each other to permit engagement into the rings 45 of the wedge-shaped or frusto-conical keys 46. The said keys 46 are clamped in the rings 45, being driven into the same by having their widened extremities 47 struck with a mallet or the like. Such a link between adjoining rows of supports is particularly easy to achieve, and is made possible by virtue of the small loads which are transmitted between adjoining rows as a result of the good sliding qualities obtained between the surfaces of the wedge plates and between those of the plank sole of the upper plate and the base, the sliding action being of the metal-to-metal type. In effect, the keys 46 with the co-operating rings 45 provide a good alignment of the keel-blocks when the latter are mounted on the ground. As explained hereinabove the sliding qualities between the wedge plates and the adjacent plates are good, on the contrary, the base plates 22, 23 cannot slide on the ground considering their large surfaces and the friction characteristics of the contact with the ground.

Calculation and practical experience both indicate that any risk of the lower and upper surfaces of a wedge respectively sliding over the upper plate of a base and the sole of a plank, is very small. For indeed the friction forces involved are considerable, so that there is very little chance of the wedge slipping between the sole of the plank and the upper plate of the row of barrels forming the base. In order, however, to prevent any incipient slip, means are provided to immobilize the top of the wedge with respect to the sole of the supporting plank, and the bottom of the wedge with respect to the inclined plate of the base. In the example shown diagrammatically in FIGURE 1 (and more in detail in operative condition, in FIGURE 1B), the said means consist of stirrups which girdle the transverse edges of the wedge plates that are in contact with the plank soles and the inclined plates of the barrels, respectively. Such stirrups retain the outer edges of the plates and prevent the wedges from slipping. The securing stirrups disposed across the wedge and the plank sole, on the one hand, and across the wedge and the inclined base plate, on the other, are designated by the reference numerals 50 and 51 respectively.

In the interests of simplification and economy, provision is made so that the inclined base plate 25, the lower and upper wedge plates 34 and 35, and the plank sole 40 have identical thicknesses and widths. As noted precedingly, the guiding flats 36 and 37 disposed crosswise beneath the wedge plate 34 and the guiding flats 43 likewise disposed crosswise beneath the plank sole 40 have a thickness which is at the most equal to that of the plates 25, 34, 35 and 40. The result of such a choice of thickness and width for the plates and also of dimensions for the guiding flats makes it possible to girdle their edges with a stirrup similar to that illustrated in FIGURES 1B and 7. The stirrup shown thereon consists of a frame of which the width is slightly greater than the sum of the thicknesses of the plates in contact that are to be rigidly united and of which the length is slightly greater than the width of said plates. In the example illustrated, the stirrup consists of two rectangular blocks 52 and 53 on to which are fixed e.g. by welding two strips

54 and 55, thereby forming a stirrup in the shape of a frame having the dimensions hereinbefore defined.

When it is required to dismantle one, or two, wedges in adjoining rows, the corresponding stirrups 50 and 51 are removed, and there are applied, to the wedge or wedges involved, by means of a suitably arranged jack, forces which tend to pull or push the wedge from the space comprised between the plank sole and the upper inclined plate of the base. To prevent the wedge or wedges against which are applied the forces exerted by the jack or jacks from tipping over too quickly during the dismantling operation, an additional supporting surface may be provided by utilizing a stirrup which is longer than the stirrups 50 or 51. To this end, it will be of advantage to use a stirrup of the type shown in FIGURE 8. A stirrup 60 such as is illustrated therein takes the form of a rectangular box of which one side is open. When it is desired to dismantle a wedge, the marginal edges of the plates in contact are girdled with such a dismantling stirrup 60 to enable the edges of the plates to slide therein. Provision is made in the bottom 61 of the said dismantling stirrup 60 for tapped holes 62 and 63 into which engage hexagonal-headed nipple screws or the like 64 and 65, which enable the dismantling stirrups 60 to be securely screwed to the support 12, and this is made possible by the fact that the nipples on these screws penetrate into tapped holes 66 provided in the plates 25. In this manner, the wedge is guided as it is disengaged, and accidents which would otherwise be possible during the dismantling are avoided.

The line of blocks hereinbefore described offers numerous advantages. It notably offers the particularity of comprising large empty spaces between adjoining rows of supports, into which it is extremely easy to arrange the wedge operating jacks. Access to the ship's hull is also greatly facilitated and inspections or repairs are much easier to carry out than with the lines of blocks resorting to heretofore. It will also be appreciated that when repairs or other work is to be carried out on any given part of the hull, the keel-blocks can be very easily and rapidly operated in that particular area of the hull.

While there has been described and illustrated, the presently preferred embodiment of the line of blocks according to the invention, it will be understood by those skilled in the art that many modifications or substitutions of parts may be made without departing from the scope of the invention. By way of example, the same principles could be applied to construct lines of keel-blocks wherein the rows of elements would comprise a number of barrels other than four; similarly, the shape of these barrels and the links between their base plates could differ from those described hereinabove.

What I claim is:

1. A line of keel-blocks adapted to bear plank-forming supporting elements for a ship, said line of blocks comprising, a series of substantially parallel rows of identical vertical barrels having bevelled tops and horizontal bases, each row comprising an inclined joining plate interconnecting said tops and a horizontal base plate interconnecting said bases, said parallel rows being disposed at right angles to the longitudinal axis of the line of blocks and resting on the ground by means of said base plates, two adjacent rows having their top joining plates inclined in opposite directions, in symmetrical relationship with respect to a vertical center plane located between and extending parallel to said two adjacent rows, and a series of parallel rows of wedge means, each row comprising

identical vertical barrel means and having horizontal tops and inclined bottoms, an upper plate connecting said horizontal tops and a lower plate connecting said inclined bottoms, said lower plate having the same inclination as said inclined top joining plate and being mounted in sliding engagement thereupon, each of said plank-forming supporting elements resting on each of said upper plates, jacking means being provided to apply pulling or pushing forces respectively between two adjacent rows of wedge means in order to engage or disengage said wedge means between said top joining plates and said plank-forming supporting elements respectively, and corresponding rows of wedge means each resting on said inclined joining plate through the medium of a bottom plate which has a matching degree of inclination and being provided at its summit with a top plate which is substantially horizontal when the wedge rests on the row of corresponding barrels, the top plate of each wedge in turn supporting planks, in such a manner that by applying temporary pulling or pushing forces it be possible to engage or disengage said wedge means in order to respectively clamp or dismantle the corresponding row in the line of blocks.

2. A line of blocks as claimed in claim 1 wherein said barrels consist of tubular elements which are joined together transversely by substantially vertical plates which form spacers.

3. A line of blocks as claimed in claim 1 wherein reinforcing angles are provided at the lower part of said barrels and are fixed to said barrels and to said horizontal base plates supporting the same.

4. A line of blocks as claimed in claim 1 wherein said horizontal base plates supporting the barrels of adjoining rows are interconnected by means of dismountable key-forming means.

5. A line of blocks as claimed in claim 1 wherein said top joining plates, said upper and lower plates and a sole plate solid with the plank are substantially of equal length and equal width and form portions projecting laterally beyond each side of the rows constituting the line of blocks.

6. A line of blocks as claimed in claim 5 wherein guide-forming slideways are provided on the external lateral edges of at least some of said plates, said slideways cooperating with the corresponding lateral edges of adjacent plate.

7. A line of blocks as claimed in claim 5 wherein stirrups which girdle the projecting portions of two adjacent plates constitute removable means adapted to render the component parts of each row mutually interconnected.

8. A line of blocks as claimed in claim 7 wherein said stirrups consist of frames, the lengths of which are substantially equal to the width of the plates to be rendered mutually interconnected and the widths to the sum of the thicknesses of said plates.
